RAIL WITH REVERSIBLE HEAD

Filed Feb. 12, 1930

Inventor:
Frank J. Hawley
by his Attorney

UNITED STATES PATENT OFFICE

FRANK J. HAWLEY, OF BROOKLYN, NEW YORK

RAIL WITH REVERSIBLE HEAD

Application filed February 12, 1930. Serial No. 427,674.

- This invention relates to railroad rails, particularly to that form thereof adapted for use with street railways, the object of the invention being to provide an improved 5 rail having a detachable head so connected that the head can be readily and expeditiously removed without the necessity of tearing up any appreciable part of the street surface.
- 10 A further object of the invention is the provision of an improved rail having a detachable and reversible head so constructed that the head may be quickly assembled in a simple and rigid manner, and in which the head may be easily removed and reversed or another head substituted therefor and in which the connecting means between the head and the base is simple in construction, efficient in use and readily accessible.
- 15 A further object of the invention is the provision of an improved two-part rail comprising a base and a detachable head connected by vertical bolts located midway between the head and the base thereby facilitating the ready removal of the head, or the reversal thereof, or the substitution of a new head therefor.
- 20 Railroad rails, as used today in streets necessarily have the tread surfaces flush with the street surface, consequently when a new rail is needed it is necessary to break and tear up the road bed or the street surface which is extremely costly, and not only that but it interferes with traffic and is usually the subject of considerable comment on the part of the citizens due to the repeated tearing up of the streets.
- 25 One of the difficulties with rails having detachable heads is the manner in which the detachable head is connected to the base and which has materially prevented the adoption of such forms of rails. Heretofore these connections have usually been such 30 that it was necessary to tear up a considerable portion of the street in order to get at the connecting bolts. This, of course, requires time, labor and money and in addition, results in considerable interference 35 with the proper use of the streets by pedes-
- trians and vehicles so that any connection between the head and the base requiring the tearing up of any appreciable portion of the street surface is impracticable, and consequently, a practical structure of this kind necessitates a rigid one and one in which the connection between the head and the base is readily accessible and can be utilized without the destruction of the road bed or any material part of the street surface, for 40 as is well known, railroad rails used in the streets necessarily have the tread surfaces flush with the street surface.
- 45 In the present improvement the rail head is connected to the base by a simple system of vertical bolts located midway between the base and the head with the head or nuts within a channel of the head, the head thus having a pair of spaced tread portions, one at each side of the bolts whereby when one side becomes worn or broken the head may be reversed or when both sides become worn or broken the head may be readily removed and this removal may be made without the necessity of tearing up any material part 50 of the street surface and therefore, at a good deal less expense than is required for the renewal of an entire rail having an integral head and base, or the renewal of the head connected by transverse bolts located below the surface of the street, and which form of connection requires the destruction of the road surface and the concrete to get at such transverse bolts.
- 55 In the drawings accompanying and forming a part of this specification—
- Fig. 1 illustrates a side view of one form of this improved rail;
- Fig. 2 is a cross section thereof taken on line 2—2 of Fig. 1;
- Fig. 3 illustrates a side view of another form of this improved rail;
- Fig. 4 is a cross section view taken on line 4—4 of Fig. 3; and
- Fig. 5 is a perspective view of another form of this improved rail.
- Similar characters of reference indicate corresponding parts in the several views.
- Before explaining in detail the present improvement and mode of operation there. 100

of, I desire to have it understood that the invention is not limited to the details of construction and arrangement of parts which are illustrated in the accompanying drawings, since the invention is capable of other embodiments, and that the phraseology which I employ is for the purpose of description and not of limitation.

This improved rail comprises a base 2 having side flanges 3 for the reception of the usual holding spikes 4 by means of which the base is secured to the cross ties, and a detachable head 5 fitting such base and which head is shown as reversible. In the present improvement the base is lengthwise channeled or recessed, as at 6, to provide a pair of webs 7 having diverging inner side faces 7' forming what may be termed a V or wedge shaped channel or recess. The head of the rail is provided, at the top thereof, with a lengthwise extending channel or recess 8 located midway of its width, thus forming a pair of similar tread surfaces 9 and 9'. This head has a depending web 10 conforming to the channel or recess in the base, and therefore, is of tapered or wedge form, adapted to snugly fit the recess or channel in the base. For detachably connecting the head and base suitable vertically located bolts 11 are provided, the heads or nuts of which are located in the channel 8 of the head and preferably in suitable recesses 12 thereof.

In certain instances these connecting bolts may be first passed through the base, with the heads thereof fitting into recesses 13 at the bottom of the base and the nuts thereof in the recesses 12 of the head, or this may be reversed so that the heads of the bolts are located in the recesses 12 of the head, while the nuts are located in the recesses 13 of the base, or if preferred, the base may be provided with nut receiving openings 14 at the bottom of the channel 6, (see Fig. 2), for the reception of nuts prior to the application of the head to the base and then the bolts passed through the head for engagement with the nuts. The recesses at the bottom of the channel 8 have sufficient size to permit the turning of the bolt heads or nuts located therein while the recesses 13 or 14 in the base are of a size to prevent the turning of the nuts or bolts during the tightening of the nuts and in practice, split washers or other means may be used to prevent jarring loose.

In practice the base webs 7 are provided with transverse bolt openings 15 adjacent to the ends of the rail for the reception of fish plate bolts 16, the heads of which are preferably located in registering recesses 16' formed in the opposed webs of the head and base, thus likewise facilitating the tightening of the nuts.

Various forms of fish plates 17 may be used. In Fig. 2 the fish plates are flush

with the sides of the detachable head. In Fig. 4 the fish plates are located in recesses 18 of the base, whereby the head of the rail may overlap the base and thus provide means for lifting the rail head from the base, which may also be accomplished by providing in the side faces of the rail recesses 19 (see Fig. 5), for the reception of cant-hooks.

In the form shown in Fig. 5, the top edges 20 of the base webs 7 and the overlapping portions 21 of the head are inclined downwardly and outwardly thereby forming a water shed to prevent the passage of water between the head and the base.

In the form of rail shown in Fig. 4, the tapered side faces of the web of the head and base terminate in straight faces, as distinguished from the continuous tapered faces shown in Figs. 2 and 5. In practice the rail heads may be assembled with the bases so as to break joint therewith, whereby a pair of heads and a pair of bases may be effectively tied together.

The present improvement not only prolongs the life of this improved railhead to twice its normal life, since it may be readily reversed without removing the entire rail with its base and not only reduces the cost of replacing it, since a large part of the street does not have to be torn up with the consequent cost of relaying it, but the improvement is so constructed that the head may be easily and expeditiously removed without the necessity of tearing up any appreciable part of the street surface causing an obstruction to traffic. Thus aside from the simple and efficient mode of connection, the rail is extremely practical and overcomes the disadvantages heretofore present in the use and of detachable heads for street railroad rails, and has been considered by railroad engineers as solving the problem of providing a readily removable head for railroad rails of this kind and is quite a step in advance over those forms of railroad rails heretofore patented having a detachable head, which for one reason or another have been considered impracticable and which no doubt has prevented the adoption and commercial success thereof.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A railroad rail comprising a base and a detachable head joined together by means

- located substantially centrally of the width of the head and extending substantially to the bottom of said base.
2. A railroad rail comprising a base and a detachable and reversible head joined together by means located substantially centrally of the width of the head.
3. A railroad rail comprising a base and a detachable head having a lengthwise extending recess or channel located midway of the head, said head and base joined together by means located in said channel and extending substantially to the bottom of said base.
4. A railroad rail comprising a base and a detachable and reversible head having a lengthwise extending recess or channel midway of the width of the head, said head and base joined together by means located in such channel.
5. A railroad rail comprising a base having a pair of webs forming a V-shaped channel, a detachable head having a similarly formed web fitting said channel and means located substantially centrally of the width of the head and base for connecting said head and base together.
6. A railroad rail comprising a channeled base forming a pair of webs, transverse bolt openings in said webs, a detachable head having a web adapted to fit the channel of said base and means passing centrally through the head and base from top to bottom thereof for connecting said head and base.
7. A railroad rail comprising a channeled base forming a pair of webs, transverse bolt openings in said webs, a detachable head having a web adapted to fit the channel of said base and means passing centrally through the head and base from top to bottom thereof for connecting said head and base, said head having a lengthwise extending recess in the top thereof midway of the width of the head for the reception of said connecting means.
8. A railroad rail comprising a channeled base forming a pair of webs, transverse bolt openings in said webs, a detachable head having a web adapted to fit the channel of said base and means passing centrally through the head and base from top to bottom thereof for connecting said head and base, said head having a lengthwise extending recess in the top thereof midway of the width of the head for the reception of said connecting means and said head having means for facilitating the lifting thereof.
9. A railroad rail comprising a channeled base forming a pair of webs, transverse bolt openings in said webs, a detachable head having a web adapted to fit the channel of said base and means passing centrally through the head and base from top to bottom thereof for connecting said head and base.
10. A railroad rail comprising a base and a detachable head said base and head having interlocking webs, the top edges of the base webs and the corresponding surfaces of the head having outwardly and downwardly inclined faces for shedding water.
11. A railroad rail comprising a base and a detachable head, said base and head having interlocking webs, the top edges of the base webs and the corresponding surfaces of the head having outwardly and downwardly inclined faces for shedding water and means located centrally of the head and base and extending from the top to the bottom thereof for connecting the head and base together.
12. A railroad rail having a flanged base and provided with a channel located midway of the width thereof of different widths and a detachable head having a web of different widths fitting said base channel and means located midway of the base and head and extending from the top of the head for connecting said head and base.
13. A railroad rail comprising a base provided with a pair of webs forming a channel or recess, said webs having transversely located bolt openings and a detachable head having a web fitting the recess of said base, said base having recesses in the top thereof for the reception of vertically located bolts for connecting the head and base together.
14. A railroad rail comprising a base provided with a pair of webs forming a channel or recess, said webs having transversely located bolt openings and a detachable head having a web fitting the recess of said base, said base having recesses in the top thereof for the reception of vertically located bolts for connecting the head and base together, and said head having recesses for the reception of the bolt head or nuts.
15. A railroad rail comprising a base and a detachable head joined together by means located substantially centrally of the width of the head said head having means for lifting the same.
16. A railroad rail comprising a base and a detachable and reversible head joined together by means located substantially centrally of the width of the head, said head having means for lifting the same.
17. A railroad rail comprising a base and a detachable head joined together by means extending adjacent to the bottom of the base and accessibly located at its upper end whereby the head may be removed without

the necessity of tearing up any appreciable part of the street surface.

18. A railroad rail comprising a base and a detachable and reversible head joined together by means accessibly located whereby the head may be removed and reversed without the necessity of tearing up any appreciable part of the street surface.

19. A railroad rail comprising a base and a detachable head joined together by means extending vertically through the head and base to near the bottom of said base whereby it is accessibly located without the necessity of tearing up any appreciable part of the street surface.

20. A railroad rail comprising a base and a detachable channeled head having interlocking web portions, the web portions of the base having transverse bolt openings for the reception of fish plate bolts and the web portion of the head and the body of the base having vertical openings for the reception of bolts for connecting the head and base together.

25. Signed at Room 1822, 15 Park Row, city, county, and State of New York, this 11th day of February, 1930.
